US00D865224S

(12) **United States Design Patent** (10) **Patent No.:** **US D865,224 S**
(45) **Date of Patent:** **** Oct. 29, 2019**

(54) **SOUND BARRIER PANEL**

(71) Applicant: **SOUND FIGHTER SYSTEMS, LLC**, Shreveport, LA (US)

(72) Inventors: **Patrick W. Harrison**, Shreveport, LA (US); **Ben J. Burkett**, Shreveport, LA (US); **Murray R. Stacy**, Flower Mound, TX (US)

(73) Assignee: **Sound Fighter Systems, LLC**, Shreveport, LA (US)

(**) Term: **15 Years**

(21) Appl. No.: **29/647,645**

(22) Filed: **May 15, 2018**

(57) **CLAIM**

The ornamental design for a sound barrier panel, as shown and described.

DESCRIPTION

FIG. 1 is a top front perspective view of a sound barrier panel showing our new design;

FIG. 2 is a top back perspective view of the sound barrier panel of FIG. 1;

FIG. 3 is a front elevational view of the sound barrier panel of FIG. 1;

FIG. 4 is a back elevational view of the sound barrier panel of FIG. 1;

FIG. 5 is a right side elevational view of the sound barrier panel of FIG. 1;

FIG. 6 is a left side elevational view of the sound barrier panel of FIG. 1;

FIG. 7 is a top plan view of the sound barrier panel of FIG. 1;

FIG. 8 is a bottom plan view of the sound barrier panel of FIG. 1; and,

FIG. 9 is a top front perspective view of the sound barrier panel of FIG. 1 in a position of use, stacked to form a sound barrier. The broken lines depicting two additional panels illustrates environmental subject matter that forms no part of the claimed design.

1 Claim, 7 Drawing Sheets
